(57) **CLAIM**

We claim the ornamental design for a string shooter, as shown and described.

DESCRIPTION

FIG. 1 is a perspective view of a string shooter showing the new design, shown from the front, top, right;

FIG. 2 is another perspective view thereof, shown from the rear, bottom, left;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dot-dash broken lines illustrate boundaries of the claim that form no part of the claimed design. The evenly spaced dash-dot broken lines illustrate portions of the string shooter that form no part of the claimed design.

1 Claim, 7 Drawing Sheets
